GAME BOARD

Alfred Wickman, Gardner, Mass.

Application January 31, 1934, Serial No. 709,153

6 Claims. (Cl. 273—119)

This invention relates to a game board based on the well known game of hide-and-seek.

The principal objects of the invention are to provide means whereby all of the features of said game can be reproduced and acted out on the game board; to provide means whereby each player can hide a playing piece on the board; means whereby the party who is "It" can try, in substantially the usual way, to find the hiding places of these pieces; means whereby each player has an opportunity to get "In Free", and means for automatically sounding a signal in either event.

Other objects and advantages of the invention will appear hereinafter.

Reference is to be had to the accompanying drawings, in which

Fig. 1 is a plan of a board with a part of it broken away to show interior construction below 20 and with parts in section;

Fig. 2 is a side view of the board to show the position in which it is located;

Fig. 3 is a view of the electrical and mechanical connections underneath the board for giving the 25 two kinds of signals;

Fig. 4 is an enlarged sectional view on the line 4—4 of Fig. 1, and

Fig. 5 is an enlarged sectional view on the line 5—5 of Fig. 1.

The game board 10 is a flat board mounted at 30 an inclination at the top of the box 11 which supports it. It is provided with a series of perforations 12 through which the players introduce their game pieces for the purpose of hiding them and a central perforation 13 at the bottom through which the goal can be seen. This constitutes the entire board, the perforations 12 being distributed around in a more or less irregular manner, as indicated.

A plate 14 underneath the board 10 is located 40 at the same angle so as to be spaced from it the same distance at all points and is also supported by the box 11. This plate 14 is provided with a central channel 15 down the center of it and a series of branch channels 16 projecting upwardly 45 from it in various directions and all slanting toward it from above. These channels 16 are either single or multiple and each one is provided with an enlargement 17 directly under one of the perforations 12. Each branch channel also is provided with an upwardly extending elbow 18 and with a depression or pocket 19 located at a lower level than the elbow and beyond it. This pocket has to be designed in certain proportions with respect to the game pieces. These game pieces pref-

erably are in the form of balls 20 of steel or other metal so that they conduct electricity and have considerable weight, each being marked as by stamping a numeral or letter upon it.

When one of these balls 20 is inserted in a hole 12 and pushed toward the adjacent end of the board by the player, it will pass around the elbow 18 of that channel and down into the pocket 19 where it comes to a stopping place at the end of the pocket against a metal plunger 21. This plunger is located on a rod 22 which is slidable in a metal conducting collar 23 fixed in stationary position. The rod is provided with a head 24 on the outside of the plate 14 having a spring 25 under it to hold it back in the position shown in the drawings.

In the channel 16 at a point near or in the elbow is a conducting stud 26 or rather the head of a stud. The collars 23 are all connected with an electric wire or series of wires 27 which pass to a battery 28 and these collars constitute one terminal of a circuit. The studs 26 constitute the other terminals and all are connected by similar wires 29 with an electric bell-operating magnet at 30. The other terminal of this magnet is connected by a wire 31 with the battery 28.

It will be seen, therefore, that when, for any reason, one of the collars 23 is electrically connected with one of the studs 26, this circuit will be completed and the magnet at 30 will operate 85 a clapper 32 and sound the bell 33.

Now, it will be seen, that when a ball 20 is placed in a pocket in the position shown in several places in Fig. 1 and the party who is "It" pushes another ball through the proper opening 90 12 up to a position it will engage the hiding ball 20, as indicated in dotted lines in several places. The "It" ball will contact with that terminal or stud 26 and with the hiding ball 20 which, as already stated, is in contact with the plunger 95 21. Therefore, a circuit is completed and the bell sounds, indicating that "It" has caught one of the players.

Now if, while "It" is endeavoring to catch a player by trying the various openings 12, another player, who has hidden his ball, pushes the head 24 of that plunger, he can push his ball out of the pocket by means of the plunger 21 over the shoulder 18. This ball will then descend by gravity into the channel 16 and into the channel 15, these channels being inclined. The channel 15 extends under the opening 13 and the ball will enter the channel and strike a movable plate 34 which constitutes the goal. This movable plate, shown as fixed on the sliding 105 110

rod 35, is held in position by guides 36. This rod is connected as by a flexible connection 37 to a bell clapper 38 and normally is held in inoperative position by a spring 39. The impact of the ball 5 against the plate 34 will operate the clapper and it will sound against the same bell 33 showing that one of the players is "In Free".

It will be seen that this game can be played indoors and that it has all the features of the 10 game hide-and-seek perfectly reproduced. The board is constructed of two parts not likely to get out of order, the playing pieces are convenient and practically indestructible and it requires very little mechanism and a simple system 15 of wiring, all the terminals 26 being on one wire and all the terminals 23 being on another. The operation of getting "In Free" requires no mechanism as the ball comes against the goal post 34 by the action of gravity. This constitutes a simple and amusing game. 20

Having thus described my invention and the advantages thereof, I do not wish to be limited to the details herein disclosed, otherwise than as set forth in the claims, but what I claim is:

25 1. As an article of manufacture, a game board comprising a board higher at one end than at the other having a series of perforations therethrough, a plate underneath the board having a series of pockets therein with which the perforations communicate, each pocket having a channel extending downwardly therefrom, said pockets being adapted to receive game pieces inserted through the perforations, an electric contact against which a conducting game piece rests 30 when introduced into a pocket, a contact located above the first contact and in position to be engaged by a second conducting game piece when introduced into the channel far enough to engage the first game piece, an electric circuit connected with the second contact, and means whereby, when two game pieces are in position 35 in contact with each other in a pocket, the circuit will be completed by said game pieces and a signal will be given. 40

45 2. As an article of manufacture, a game board comprising a plate higher at one end than at the other having a main channel extending down the plate and a series of branch channels therein, each branch channel having a downwardly extending pocket at its end for the reception of a conducting game piece, an electric contact against which the game piece is held by gravity, a second electric contact in the channel spaced from the first sufficiently to insure that the introduction of a second conducting game piece 50 in contact with the first one will cause the second game piece to engage the second contact, a battery, a signal device, a circuit connected with the first contact, and a circuit connected with the second contact, said circuits being connected with the signal device to operate it when the entire circuit is completed by the contact of the two game pieces with the electrical contacts on the board. 55

60 3. As an article of manufacture, a game board comprising a slanting board having a series of perforations therethrough, a plate underneath the board having a series of pockets therein, each pocket having a channel extending downwardly

therefrom, said pockets being adapted to receive game pieces inserted through the perforations, an electrical contact against which a metallic game piece rests when introduced into a pocket, a contact located above the first contact and in position to be engaged by the second metallic game piece when introduced into a channel far enough to engage the first game piece, an electric circuit connected with the second contact, means whereby, when two game pieces are in position in contact with each other in a pocket, the circuit will be completed by said game pieces and a signal will be given, and mechanical means for operating the signal device when the first game piece is pushed out of its channel so as to run down the channels to the bottom of the board. 80

85 4. As an article of manufacture, a game board comprising an inclined plate having a central channel and a series of branch channels therein, each branch channel having a downwardly extending pocket at its end for the reception of a metallic game piece, an electric contact against which the game piece is held by gravity, a second electric contact in the channel spaced from the first sufficiently to insure that the introduction of a second metallic game piece in contact with the first one will cause the second game piece to engage the second contact, a battery, a signal device, a circuit connected with the first contact, a circuit connected with the second contact, said circuits being connected with the signal device to operate it when the entire circuit is completed by the contact of the two game pieces with the electrical contacts on the board, and mechanical means for operating the signal device when the first game piece is pushed out of its channel so as to run down the channels to the bottom of the board. 90

95 5. As an article of manufacture, a board for a game to be played with metal balls comprising a plate located at an inclination and having a channel extending longitudinally and branch channels extending upwardly therefrom, said branch channels having pockets for receiving game pieces, a goal located at the bottom of the main channel and movably mounted, a bell, a clapper for the bell, means for connecting the clapper with the goal, whereby the motion of the goal will operate the clapper and sound the bell, two contacts in each pocket spaced apart such a distance that they will be electrically connected by two balls located in the pocket, and electrical connections for sounding the bell electrically when two balls are placed in a pocket in contact with each other. 100

105 6. In a game, the combination of a plate located at an inclination, a main channel extending down along the center thereof, branch channels extending upwardly from the main channel and each having a downwardly extending pocket from the top thereof, game pieces in the form of metallic balls, a signal bell, means whereby when a game piece runs down a branch channel by gravity and down the main channel, the bell will be operated mechanically, and means whereby, when two of said balls are placed in any one of the pockets in contact with each other, said bell will operate electrically. 110
